LIQUID REAGENT FEEDER

Albert J. Almquist, Philipsburg, Mont.

Application April 19, 1939, Serial No. 268,828

1 Claim. (Cl. 137—104)

The present invention relates to the proportional feeding of liquid and is designed particularly for use in the feeding of liquid reagents in mill flotation apparatus, as well as for other purposes.

An important object of the present invention is to provide a liquid reagent feeder of this character embodying a simple and practical adjustment means to regulate the feeding of the liquid from a few drops each minute to a materially increased volume, and which at the same time is efficient and economical in operation and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a top plan view.

Figure 2 is a longitudinal sectional view taken substantially on a line 2—2 of Figure 1.

Figure 3 is a vertical sectional view through one of the compartments showing the adjusting means for the float.

Figure 4 is a fragmentary sectional view of the float control valve.

Figure 5 is a detail of the nozzle connection.

Figure 6 is a detail of the cam and lever for adjusting the float, and

Figure 7 is a side elevational view of the guide for the vertical adjustment of the float.

Referring now to the drawings in detail, wherein for the purpose of illustration I have disclosed a preferred embodiment of the invention, the numeral 5 designates a reservoir tank adapted to contain the supply of reagent liquid having a drain pipe 6 extending upwardly through the bottom thereof with the intake end of the drain pipe terminating above the bottom of the reservoir, the other end of the pipe 6 being threadedly connected to a nipple 7 positioned in the bottom of a tank or chamber 8 which is supported below the horizontal plane of the reservoir 5 in order that the liquid from the reservoir may gravitate to the chamber 8.

Secured to the inner end of the nipple 7 is a cap 9 having an opening extending therethrough and formed into a valve seat 10. A valve 11 operates with the seat 10 to control discharge of the liquid into the chamber 8 from the pipe 6, the valve including a stem 12 which projects upwardly into the chamber, said valve stem having its upper end threaded as at 13 for

threaded engagement with a float 14. The valve stem 12 also extends upwardly beyond the float 14 and is slidably through a bracket 15, said bracket including an angular depending extension 16 slidably mounted in a guide 17 secured to one of the side walls of the chamber by means of screws or the like 18.

The extension 16 is also formed with a circular recess 19 within which a disk 20 is seated for free rotation therein, the disk having a lever 21 eccentrically connected thereto and projecting through the adjacent wall of the chamber and provided with an angular manipulating end 22.

The lever 21 is journalled in a bracket 23 secured to the outer wall of the chamber, and the bracket is provided with a pair of outwardly projecting stops 24 in the path of movement of the manipulating extension 22 of the lever to limit 20 rotation of the lever in either direction.

Secured in position alongside of the chamber 8 is a second chamber 25 having communication with the chamber 8 by means of a drain pipe 26 which has its intake end projecting upwardly 25 above the bottom of the chamber 8 as clearly shown in Figure 2 of the drawings.

The discharge end of the drain pipe 26 is connected to a nipple 27 secured in position in the bottom of the chamber 25 and the said chamber 30 is provided with a control valve and adjustable float identical to that described with respect to the chamber 8 and accordingly a detailed description thereof is not deemed necessary.

A drain nipple 28 is positioned in the bottom 35 of the chamber 25 with its intake end terminating above the bottom of the chamber and to its lower end is attached a rubber hose 29 having a nozzle 30 connected thereto by means of a hollow nipple 31, the discharge end of the nozzle being 40 reduced as shown at 32 and curved in the position as clearly shown in Figure 2 of the drawings.

The nozzle 30 is supported in an upright position by means of an arm 33 which is secured intermediate the ends of a vertically extending rod 34, the upper and lower ends of the rod being slidably inserted in a U-shaped bracket 35 supported in position on the upper edge of the endmost chamber 25 by means of a hook 36. The upper end of the rod is threaded as shown at 37 45 for threadedly receiving a nut 38 having a manipulating arm 39 projecting therefrom. An expansible coiled spring 40 is mounted on the rod 34 with one end bearing against the arm 33 and its upper end bearing against the upper portion 50 of the bracket 35 whereby to yieldably urge the

rod 34 downwardly to maintain the nut 38 against the upper end of the bracket.

A transverse pin 41 is mounted in the nipple 7 to limit the downward movement of the valve 11.

In the operation of the device the float 14 maintains a desired liquid level in the chamber 8 by means of the valve 11 and from the chamber 8 the liquid passes into one or more of the additional chambers 25 under similar level control 10 for subsequently entering the hose 29 for discharge from the nozzle 30. The additional chamber or chambers 25 are provided to prevent any variation in the amount of liquid supplied to the nozzle 30 which might be caused when the supply of liquid in the reservoir 5 reaches an extremely low level and is suddenly again refilled. 15

The quantity of liquid discharged from the nozzle 30 which has its reduced end 32 curved downwardly, is controlled by the raising and lowering of the nozzle by means of the nut 38. 20

The adjustment of the float 14 relative to the valve stem 12 and the adjustment of the bracket

15 by means of the lever 21 control the level of the liquid maintained in the respective chambers.

5 The level of the liquid in the chamber 8 must always be maintained slightly higher than the level of the liquid in the chamber 25 in order that the latter level may be maintained constant.

It is believed the details of construction and manner of operation of the device will be readily understood from the foregoing without further detailed explanation.

Having thus described the invention, what I claim is:

In a valve structure, a valve stem, a float carried thereby, a horizontally extending attaching bracket, a cam member adapted for vertically adjusting the bracket on its supporting structure and adjustable means for suspending the stem on the bracket to limit opening movement of the valve.

ALBERT J. ALMQUIST.
